[57] CLAIM

The ornamental design of the insulated protective enclosure, as shown and described.

DESCRIPTION

FIG. 1 is a rear elevational view of the insulated protective enclosure according to our design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view thereof; and,

FIG. 8 is a front perspective view with the front door and top in open condition.

The stippled portions of the doors top and side walls depict random textured slightly raised portions of the enclosure; and the rear door is hinged similar to the front door.
